UNITED STATES PATENT OFFICE.

WATSON M. HOLMES, OF BOSTON, MASSACHUSETTS, ASSIGNOR TO THE
PLANTERS COMPRESS COMPANY, OF WEST VIRGINIA.

FEEDER FOR PRESSES.

SPECIFICATION forming part of Letters Patent No. 653,734, dated July 17, 1900.

Application filed August 24, 1899. Serial No. 728,286. (No model.)

To all whom it may concern:

Be it known that I, WATSON M. HOLMES, a citizen of the United States, residing at Boston, in the county of Suffolk and State of Massachusetts, have invented a new and useful Improvement in Feeders for Presses, of which the following is a specification.

This invention relates to an improvement in feeders for presses; and its object is to provide a yielding section to the feeder.

The invention consists in substantially the construction hereinafter described, and more particularly pointed out in the claims.

In the drawing reference-letters designate the parts with which they are connected.

The single figure in the drawing illustrates in side elevation a single feeding device forming part of the feeding mechanism, but with part of the yielding foot in section.

The feeder forming the subject-matter of the present invention is applicable to a number of different kinds of presses, but is particularly designed for use in connection with the form of press shown and described in the patent to George A. Lowry, No. 630,369, granted August 8, 1899.

In the drawing a single member of the feeding mechanism is illustrated. There should be as many feeding members as there are slots in the cap-plate of the press, and ordinarily eight slots are employed. These feeding members are adapted to be given a reciprocating movement toward and away from the slotted cap-plate by any suitable mechanism; but as this mechanism forms no part of the present invention it is not shown or described.

A designates one member of the feeding mechanism, which is constructed of any suitable material, but preferably of metal, with numerous openings through it to secure lightness, as shown. This feeding member should be provided with an independently-movable section at the lower portion thereof, which is designed to yield when too much cotton gets between it and the slot in the cap-plate, and thereby prevent the cotton from being packed too tight. In the form shown this movable section, which is designated by the reference-letter B, is pivoted at the inner end to the upper section of the feeding member, although this construction is not a necessary part of

the invention. Between the movable part B and the upper part of the feeding member a spring C may be placed, so as to interpose an elastic resisting medium against the movement of the member, and it has been found convenient to guide the movable part with reference to the other section of the feeding member and limit its downward throw by the guideway C', the ledge or shoulder D, and the hook E.

The operation of the device will be readily understood from the foregoing description. The feeding member is by any suitable mechanism given a suitable movement toward and away from the slotted cap-plate and serves to push the material down toward such cap-plate, and when too much material gets between the feeding member and the cap-plate or any obstruction intervenes between such parts the yielding section B will be lifted up, and thereby accommodate the feeding mechanism to the condition of affairs and prevent the packing of the material too tight or a severe impact against the obstruction.

It is obvious that persons skilled in the art may widely vary the construction above described without departing from the principle of the invention, and I therefore do not wish to be understood as limiting myself to the details shown and described.

What I claim, and desire to secure by Letters Patent, is—

1. In a machine for compressing fibrous material, a feeder having an under section pivoted to it at one end and a spring interposed between said section and feeder whereby the former is permitted to yield in an upward direction toward said feeder: substantially as and for the purpose set forth.

2. In a machine for compressing fibrous material, a feeder having an under section pivoted to it and a spring interposed between the free end of said section and the feeder whereby said feeder may be yieldingly advanced to its work: substantially as and for the purpose set forth.

3. In a machine of the class described for compressing fibrous material, a feed-plate having a length corresponding approximately to the length of the slot in which the material is to be fed, and having a lower section piv-

oted thereto at one end and otherwise free to move upward toward the main body of the feed-plate and a spring interposed between said section and feed-plate whereby the latter may be yieldingly advanced to its work: substantially as and for the purpose set forth.

4. In a machine for compressing fibrous material, a feeder having a foot pivoted at one end thereto and guided thereon at its other end, with an interposed spring; substantially as and for the purpose set forth.

5. In a machine for compressing fibrous ma-

terial, a feeder having a foot movable with reference thereto, an interposed spring, a guideway, and a stop to limit the downward movement of the foot; substantially as and for the purpose set forth. 15

In witness whereof I have hereunto set my hand, this 21st day of August, 1899, in the presence of the subscribing witnesses.

WATSON M. HOLMES.
